UNITED STATES PATENT OFFICE.

ALFONSO CORTELLA, OF NICE, FRANCE.

COMBINED SOUND-REPRODUCING AND MOVING-PICTURE MACHINE.

1,331,049.

Specification of Letters Patent. Patented Feb. 17, 1920.

Application filed August 21, 1913. Serial No. 785,853.

To all whom it may concern:

Be it known that I, ALFONSO CORTELLA, a subject of the King of Italy, resident of Nice, France, (and whose post-office address is No. 172 Leyden St., East Boston, Mass.,) have invented an Improvement in Combined Sound - Reproducing and Moving - Picture Machines, of which the following description, in connection with the accompanying 10 drawings, is a specification, like characters on the drawings representing like parts.

This invention relates to combined sound reproducing and moving picture machines and aims to provide a novel combination of 15 a sound reproducing or talking machine having a plurality of preferably continuously operative record carrying members carrying successively operative records, either disk or cylinder, and a moving picture machine whereby a plurality of records 20 may be played without substantial interruption in synchronism with a suitable series of pictures to provide a reproduction of any desired length within the capacity of the 25 picture machine.

It is preferred that the pictures be taken at the time the record is made and synchronously therewith, so that the pictures and record may be reproduced in substantially absolute synchronism without the necessity of providing any special synchronizing means and my invention is herein illustrated as embodied in a machine of that type.

Referring to the drawings of an illustrative embodiment of my invention comprising a talking machine of the disk record type to be described herein,

Figure 1 is a front elevation of my improved combined talking and moving picture machine, the latter, which may be of any conventional form, being shown as broken away;

Fig. 2 is a plan view of the same;

Fig. 3, a front elevation of the shift mechanism for throwing the records successively into and out of operation;

Fig. 4, a plan view thereof;

Fig. 5, a vertical section on the line 5—5, Fig. 3 from the right showing a detail of a 50 portion of the means for locking a record into operative relation with its carrying member, herein a turn-table;

Fig. 6, a vertical sectional view on the line 6—6, Fig. 3, of further details of the 55 shift mechanism;

Fig. 7, an enlarged detail of the record locking clutch; and

Fig. 8, a side elevation of one of the turn-tables, with the sound arm mounting in vertical section, and showing also the connection between the sound arm and shift mechanism to actuate the latter for successively locking and unlocking the records to their respective turn-tables.

Referring now to Figs. 1-3, the talking 65 machine comprising one member of my invention is shown as comprising a suitable table or stand 1, conveniently supported, as by hollow legs 2 adapted to receive therein sliding rods 3, which may be adjustably 70 locked thereto by means of set screws 4 so that the table may be adjusted to any height, to suit varying conditions as desired.

Mounted on the table 1, Figs. 1-2, at suitable points are a plurality, herein two, of 75 turn-table supports or frames 5, 5, which may be secured to the table in any convenient manner as by bolts 6, 6. The top member 7 of each frame, and also the bottom member 8 are each drilled vertically to provide bearings for the hollow turn-table shaft 9 which rotates therein. Each shaft 9 may be, if desired, provided with roller bearings 10.

Adjacent the shafts 9, 9, and herein, in the rear of the same, Figs. 1, 2 and 3, is 80 located a common driving shaft 11 for jointly and synchronously operating the talking and picture machines and provided with a pulley 12, by means of which power may be transmitted to said shaft from any 85 convenient source, as a motor 12^a, for instance, beneath the table 1. The shaft 11, see Fig. 2, is provided with a plurality of gears 13, 13, each in mesh with a gear 14 on one of the shafts 9, whereby rotation is 90 imparted to the turn-tables 15, 15, mounted on the upper ends of said shafts.

The turn-tables 15, 15, are both adapted to be, and preferably are, always in rotation with the shaft 11, as will be more fully described later, and may conveniently be termed simultaneously operating record carrying members, while the records 16, 16, are adapted to be held secured to their respective successively operating record supports 105 or carrying members 17, 17, and successively locked to the turn-tables at the proper times by a novel means for that purpose. The record carrying member 17 is here shown, see Fig. 7, as a pintle mounted within the 110

shaft 9, normally freely rotatable therein and extending above and below the same, and provided on its upper end with a nut 18 for locking the record between the same 5 and a ring or shoulder 19 on the pintle 17. The upper end of each shaft 9 is provided with a shoulder 9^a, Fig. 7, for securing the turn-table thereto and said upper end is counter-bored and provided with a crown 10 gear 20, and each ring 19 is provided with a single depending tooth 21, Fig. 7, adapted to engage the crown gear 20 when the record is in operation.

For both unlocking the record carrying 15 member 17 from the turn-table and its shaft, and for supporting the same while in unlocked or inoperative position, I have provided the following novel construction. Just below the lower end of each shaft 9, Figs. 20 1, 3, is a pintle and record supporting member 22, which normally supports the lower end of the pintle when in inoperative position with its tooth 21 raised above and out of engagement with the crown teeth 20, as 25 at the right hand end of Fig. 1; but which, when the pintle is in operative position, as at the left, see Fig. 1, is dropped somewhat below the end of the pintle, permitting the latter to drop down in the shaft 9 and the 30 tooth 21 to engage the crown teeth 20, Fig. 7, and lock the record 16 to its turn-table 15 and shaft 9, and to cause it to rotate with said turn-table and shaft.

As previously stated the two turn-tables 35 are so connected with the operating shaft 11 that they are both always in operation but I have provided novel record shifting means, including the pintle supports 22, 22, just referred to, for alternately throwing 40 the pintles and the records secured thereto into operation and this record shifting means I will now describe. It will be obvious that it is particularly desirable that means be provided that will shift the records 45 so quickly that no noticeable interruption in the reproduction thereof will occur. At any suitable point, therefore, between the two turn-tables, and preferably substantially midway thereof, is provided a support 50 23 on the table 1, for the shifting lever or walking beam 24, which is pivoted thereto by a pin 25. This support 23 is, in this case, an angle iron, Fig. 6, having a base 23^a and rear upturned member 23^b provided with 55 lever guides 23^c. The lever 24 is preferably a long thin member provided at each end, at suitable points thereon, with the pintle supports 22, 22, previously referred to, and secured thereto as desired as by screws 26, 60 Fig. 5.

It will be noted from the construction so far described that necessarily when one end of the lever 24 is depressed, with its corresponding pintle support, the opposite end, 65 with its corresponding pintle, is raised so

that necessarily one pintle with its record is locked to its shaft 9 while the opposite pintle and its record is unlocked from its shaft 9. The controlling means for the shifting mechanism herein comprises bell-crank locking and unlocking levers 27, Figs. 3, 4, 6 pivoted to suitable supports 23^b on the table 1, the short arm of each lever being bent or otherwise adapted to engage a catch 28, on the rear face of the lever 24 while the long arm of the lever is extended to form a cam surface 29 adapted to be engaged by a lever tripping member 30 depending from and adapted to be actuated by the sound arm, see Fig. 2, in dotted lines, to be more fully described presently. These levers 27 are each normally retained in locking position by means of a leaf spring 31 secured thereto and seated upon the table 1.

For depressing and locking one end of the lever 24 instantly upon the unlocking and raising of the opposite end of said lever and thus instantly shifting the records, I have invented the following novel mechanism, forming also part of the shifting lever controlling means. On the front face of the lever 24, see Figs. 3, 4, 5, near each end is secured a bracket 32 and to the brackets are pivoted rearwardly extended lever positioning members 33, 33^a. These lever positioning members 33, 33^a are somewhat narrower at their rear ends than at their forward ends; see Fig. 4, and each has pivoted thereto and substantially parallel therewith a yieldingly mounted catch 34 provided with a slot 35 on one edge thereof to engage a pin 36 on the lever positioning member 33 and each catch is normally held in that position by a leaf spring 37 thereon bearing against a pin 38 also extended upwardly on the lever 33, and acting as a stop on that side of the member 34 for the same.

Between said members 33, 33^a, on the member 23^b are pivoted two upright reversing levers 39, 39, each suitably positioned to be engaged by one of the trip members 30, 30, immediately after the member 30 depresses the cam end of one of the locking levers 27, 27. These reversing levers 39, 39, are each pivotally connected by a connecting rod 40 with the lever positioning member 33 or 33^a at the opposite end of the lever 24, and are each normally retained in position by a spring 41, secured thereto and to the member 23^b or any convenient support. For positively acting upon the shifting lever positioning members 33, 33^a, at the proper time and causing them to depress the respective ends of the lever 24, I have provided lever shifting disks 42 mounted upon and rotated by the shaft 11. These disks may be adjusted upon the shaft 11 both longitudinally and circumferentially by means of screws 43. Each disk has a roll 44 mounted thereon which, on rotation of the disk 42, will 130

engage the upper face of the lever positioning member 33, or 33^a when it is in proper position for said engagement, to depress one end of the lever 24 and its pindle 5 supporting member 22 and thus also act to raise the opposite end of the lever 24, its pindle support and pindle.

The trip members 30, 30, are shown, Fig. 8, as depending rods with laterally bent 10 ends carrying rolls 45, 45, and threaded near their upper ends and provided with nuts 46, 46, disposed, respectively, Figs. 2, 8, above and below the ends of clamp members 47, 47, secured about the necks 48, 48, 15 of the sound arms 49, 49, movably mounted in the two branches of the sound carrying tube 50.

Each trip member is so adjusted as to position on the neck 48 of the sound arm 20 that it will trip the lever 39 by its roll 45 being pushed against the same by the traveling sound arm 49 when the needle 51 of the sound box 52 thereon, having completed the reproduction of the record, is fed laterally 25 sufficiently far to cause said engagement and this result is accomplished most satisfactorily if the sound arm is deflected laterally quickly by a distorted portion 53 of the groove at the end of the record 30 groove 54.

For supporting each sound arm 49 above and out of contact with its record or turn-table when the record is to be changed, I have provided, Figs. 2, 8, on the upper end 35 of the sound conveying tube 50 and adjacent each neck 47, a cam track 55 on which the clamp 47 slides as the sound arm is swung laterally away from the turn-table, and this cam 55 gradually raises the sound 40 arm 49 and box 52 to a convenient inoperative position.

The sound tube 50, Fig. 1, is shown forked near its upper end, one arm leading to each sound arm 49. The lower end of the sound 45 tube is carried down through the table 1, extended laterally and provided, if desired, with any suitable sound magnifying device 56, and by means of a wire 57 or other convenient arrangement, the sound may be conveyed to any part of the auditorium.

The sound tube 50 is herein shown as contained within a case 58 but this may be dispensed with if desired. The shaft 11 is shown, Figs. 1, 2, as carrying at each end a 55 gear 59 either one of which is adapted to mesh with gears 60, 61, on the moving picture machine, thus permitting the talking machine to be positioned at either side of the moving picture machine as may be most 60 convenient, having in mind the construction of the picture machine and operating requirements.

The operation of my improved combined talking and moving picture machine is as 65 follows: The record is first made and the

picture taken either on the foregoing described machine by substituting a record making needle for the reproducer, and a camera for the projecting apparatus, or upon other well known machines operated 70 synchronously for that purpose. The record 16 of the first portion of the piece to be reproduced is then placed upon either turn-table, for instance the left hand one, Fig. 1. The record is secured to its pindle 75 17, see Fig. 7, by removing the nut 18 therefrom, thrusting the top of the pindle 17 therethrough and then screwing the nut down securely thereon, locking the record between the nut and the flange 19. The 80 record 16 of the balance or next section of the piece is placed in position in the same manner on the right hand turn-table. The left hand end of the lever 24 is then depressed until the tooth 28 on the rear face 85 thereof is engaged by the lever 27, thus permitting the pindle 17 to drop within the hollow shaft 9 until the tooth 21 on the flange 19 engages the crown teeth 20 on the upper end of the shaft 9.

The lever positioning members 33, 33^a will be in the position shown in Fig. 4, the right hand end of lever 24, Fig. 3, supporting the right hand pindle 17 with its record in raised or inoperative position Fig. 1. 90 Both needles are placed at the beginning of the respective records, one record being in operative position and the other in inoperative position. The motor 12^a or other source of power is now started and the turn-tables 15, 15, and moving picture machine thus put into operation by means of the pulley 12 and common shaft 11. The turn-tables and picture machine being both geared to the same operating shaft 11 are 100 positively operated in synchronism, and the record and pictures taken either on said machines or other synchronously operated machines will, of course, be reproduced in synchronism.

As already stated, the record groove is preferably provided at its end with a short lateral extension 53 and the lever tripping member 30 is so adjusted on the clamp 47 as to height, and said clamp so adjusted 110 circumferentially about the neck 48 that the roll 45 on said member 30 will engage the cam face 29 of the lever 27 to throw the same and unlock the lever 27 from the catch 28 on the lever 24 approximately an 115 instant before the needle 51 reaches the lateral extension 53 at the end of the record. The roll 45, still moving laterally, will then engage the lever 39 as soon as the record is finished and the needle enters the lateral extension 53 which causes a quick movement of the roll 45 against said lever.

When the roll 45 engages the lever 39 it then, by reason of the link 40 connecting the lever 39 with member 33^a, causes said mem- 120 125 130

ber 33^a to be thrown to the left, Fig. 4 into the path of the roll 44 on the Fig. 4, right-hand disk 42. If when said member 33^a is thus thrown laterally, the yielding catch 34 thereon should happen to engage edge-wise the roll 44, said member 34 will yield against the spring 37 until the roll has passed beyond its plane, the narrow outer end of the member 33 permitting the same, 10 when the catch 34 will be immediately thrown again into the path of the roll 44 by said spring 37. On its next revolution, or its first revolution if said edge-wise contact did not take place, the roll 44 will 15 engage the upper face of the member 34 and depress the same with that end of the lever 24 bringing the catch 28 thereon beneath the end of the spring pressed lever 27, the spring 31 throwing the lever 27 forward 20 and locking the lever 24 in that position.

When that end of lever 24 is depressed, the pintle supporting member 22 thereon is also depressed permitting the pintle 17 and record 16 locked thereto, hitherto inoperative position to fall into operative position, the tooth 21 on the pintle 17 engaging the crown teeth 20, and imparting the motion of the Fig. 1, rotating right hand turn-table to the record 16. By the same motion 30 of the lever 24, the left hand, hitherto operative, record is withdrawn into inoperative position by being raised by the rising left hand end of lever 24 and member 22 until the tooth 21 on said pintle is disengaged 35 from the teeth 20, on the shaft 9. While this record is in inoperative position, it may be replaced by a record bearing another piece or another section of the same piece or reproduction. For this purpose, the sound 40 arm may be swung to the right until it rides upon the cam 55 where it will be supported.

When the new record has been placed on the left hand pintle 17 and the needle again 45 placed in position, the record is again ready to be automatically placed in operation by a repetition of the foregoing described operation of the trip member 30, actuation of the levers 27, 39, and shifting of the lever 24, 50 raising the right pintle and record and lowering again the left hand pintle and record.

Obviously this operation of the talking machine may be continued without any 55 noticeable interruption of the reproduction of the record as long as desired, and completely overcoming the objectionable delays and interruptions hitherto occasioned by changing the records.

60 By my improved construction it is practicable for the first time, so far as I am aware, to produce a whole opera, oratorio, or any long musical production and the accompanying pictures at one time without interruption, the whole being in complete syn-

chronism. This is possible because the turn-tables are always in synchronism with the picture machine and each turn-table is automatically and mechanically thrown into operation by the mechanism operating in 70 connection with the record on the opposite turn-table.

By this means dependence upon special synchronizing means governed by the motion of the picture machine, or synchronizing means separately operated, with its accompanying uncertainties, is absolutely avoided. Where it would otherwise be necessary to synchronize the movement of the record-carrying member with the picture 80 machine after each record were placed in operation, it is, by means of my improved construction, necessary only to properly place the record on the turn-table and adjust the needle and complete synchronism is assured throughout the operation of all portions of successively operated sound records. 85

While the above embodiment of my invention provides a most satisfactory form of construction, it may be possible to vary the 90 same in many respects within the spirit of the invention and the scope of the appended claims.

Claims:—

1. The combination with a moving picture taking or reproducing machine, of a sound recording or reproducing machine comprising a plurality of automatically, successively rotatable record carrying members, a common driving shaft for the picture 95 machine and record carrying members, and means operated by the shaft for positively throwing each of the record carrying members into and out of operation in repeated cycles. 100

2. In a machine of the class described the combination with a picture taking or reproducing machine, of a sound recording or reproducing machine comprising a plurality of automatically, successively operable, 110 movable disk record carrying members, means for effecting the successive operation of said disk records in repeated cycles, and a driving shaft positively connected to both said machines whereby complete synchronism of picture and sound reproductions of a plurality of successively operated records is effected for an indefinite time. 115

3. The combination with a picture taking or reproducing machine, of a sound recording or reproducing machine comprising a plurality of continuously movable record carrying members, means for continuously moving said members, means for locking a record to each of the record carrying members in succession, and means including a driving shaft connecting the picture and sound reproducing machines for effecting the reproduction of the records in repeated cycles. 120 125 130

4. The combination with a picture taking or reproducing machine, of a sound recording or reproducing machine comprising record carrying members, means for continuously moving said members, means for locking the records to the record carrying members in succession, an operating shaft effecting continuous driving of the picture and sound reproducing machines, and means 10 including a plurality of sound boxes and their needles for effecting reproduction of the records in repeated cycles.
5. The combination with a picture taking or reproducing machine, of a sound recording or reproducing machine comprising continuously operating record carrying members, means for inoperatively positioning a plurality of records adjacent thereto, and means for automatically and substantially 15 simultaneously throwing one record out of and another record into operative position on the record carrying members in repeated cycles, and a synchronizing operative connection between said machines.
- 20 6. In a machine of the class described the combination with a picture taking or reproducing machine, of a sound recording or reproducing machine comprising a plurality of continuously moving record carrying members, means for inoperatively positioning a plurality of records adjacent thereto, means for automatically and substantially simultaneously throwing one record out of and another record into operative position 25 and repeating said operation in cycles, and a synchronizing operative connection between said machines.
7. In a machine of the class described the combination with a picture taking or reproducing machine, of a sound recording or reproducing machine having a plurality of sound record carriers acting successively axially upon the record members to remove them from operative position, and means 30 automatically effecting successive operation of the record carriers in repeated cycles, and a synchronizing operative connection between said machines.
- 40 8. The combination with a picture taking or reproducing machine, of a sound recording or reproducing machine comprising a plurality of turntables, successively operating record carrying members vertically adjustable relative thereto, and inoperatively 45 positioned relative to the turntables when in raised position, and means including a plurality of sound boxes, needles, and records effecting automatic, successive, operative positioning of the record carrying members relative to the turntables, in repeated 50 cycles, a synchronizing operative connection between said machines.
- 55 9. The combination with a picture taking or reproducing machine, of a sound recording or reproducing machine comprising a plurality of simultaneously operating record carrying members, successively operative record carrying members for holding the records in inoperative position, sound arms, means for locking the records in operative position, a plurality of sound arms, means for locking the successively operable record carrying members in operative engagement with the simultaneously operating carrying members; and record shifting means including a driving shaft connecting the talking and picture machines, and a record shifting lever for throwing one record into and a second record out of operation in repeated cycles. 70
- 60 10. The combination with a picture taking or reproducing machine, of a sound recording or reproducing machine comprising simultaneously operating record carrying members, successively operable record carrying members for holding the records in inoperative position, a plurality of sound arms, means for locking the successively operable members in operative engagement with the simultaneously operating record carrying members; and record shifting means including a driving shaft connecting the talking and picture machines, and a record shifting lever for throwing one record into and a second record out of operation in repeated cycles; and controlling means operatively connecting the sound arms with 75 the shifting lever to control the same. 80
- 65 11. The combination with a picture taking or reproducing machine, of a sound recording or reproducing machine comprising simultaneously operating record carrying members, shafts therefor, adjustable, successively operable, record carrying members for holding the records in inoperative position, a plurality of sound arms, interlocking members on the successively operable carrying members and shafts for locking the simultaneously operable carrying members into operative engagement therewith; and record shifting means including a driving shaft connecting the talking and picture machines, and a record shifting lever for simultaneously throwing one record into and a second record out of operation in repeated cycles; and controlling means operatively connecting the sound arms with the shifting lever to control the same. 90
- 70 12. The combination with a picture taking or reproducing machine, of a sound recording or reproducing machine comprising a plurality of simultaneously operating record carrying members, shafts therefor, successively operative record carrying pintles for holding the records in inoperative position, sound arms, means for locking the pintles in operative engagement with the simultaneously operating carrying members; and record shifting means including a driving shaft connecting the talking and picture machines, and a record shifting lever having pintle supports and lever positioning mem- 105
- 75 130

bers thereon for throwing one record into and a second record out of operation in repeated cycles; and controlling means including lever tripping members on the sound 5 arms to control the lever positioning members.

13. The combination with a picture taking or reproducing machine, of a sound recording or reproducing machine comprising a 10 plurality of simultaneously operating record carrying members, shafts therefor, successively operating record carrying pintles for holding the records in inoperative position, sound arms, means for locking the pintles 15 in operative engagement with the simultaneously operating carrying members; and record shifting means including a driving shaft connecting the talking and picture machines, and a record shifting lever having 20 pintle supports and lever positioning members thereon; and controlling means including reversing levers operatively connected with the positioning members, and lever tripping members on the sound arms to control 25 the reversing levers for throwing one record into and a second record out of operation in repeated cycles.

14. The combination with a picture taking or reproducing machine, of a sound recording or reproducing machine comprising simultaneously operating record carrying members, shafts therefor, successively operative record carrying pintles for holding the records in inoperative position, a plurality 35 of sound arms, and means for locking the pintles in operative engagement with the simultaneously operating carrying members; record shifting means including a driving shaft connected with the talking and 40 picture machines, and a record shifting lever having pintle supports and lever positioning members thereon; and controlling means including reversing levers for the positioning members, lever tripping members 45 on the sound arms to actuate the reversing levers; and means for locking the shifting lever to lock one record into and a second record out of operative position in repeated cycles.

50 15. The combination with a picture taking or reproducing machine, of a sound recording or reproducing machine comprising a plurality of simultaneously operating record carrying members, shafts therefor, successively operative record carrying pintles for holding the records in inoperative position; a plurality of sound arms, means for holding the pintles in operative engagement with the simultaneously operating carrying members; record shifting means including a driving shaft connecting the talking and picture machines, and a record shifting lever having pintle supports and lever positioning members thereon; controlling means including 55 reversing levers for the positioning le-

vers, lever tripping members on the sound arms to actuate the reversing levers, and locking means for the shifting lever.

16. The combination with a picture taking or reproducing machine, of a sound recording or reproducing machine comprising a plurality of simultaneously operating record carrying members, shafts therefor, successively operative record carrying pintles for holding the records in inoperative position; 70 sound arms, means for holding the pintles in operative engagement with the simultaneously operating carrying members; and record shifting means including a driving shaft connecting the picture and sound reproducing machines, a record shifting lever having pintle supports and lever positioning members thereon, and catches on the positioning members; and controlling means including reversing levers connecting the positioning members, lever tripping members on the sound arms to actuate the reversing levers, and locking levers actuated by the 75 tripping members.

17. The combination with a picture taking or reproducing machine, of a sound recording or reproducing machine comprising a plurality of simultaneously operative record carrying members, shafts therefor, successively operative record carrying pintles for holding the records in inoperative position, means for holding the pintles in operative engagement with the successively operable carrying members, and a plurality of sound arms; record shifting means including a 90 driving shaft connecting the talking and picture machines, a record shifting lever having pintle supports and lever positioning members thereon; and catches on the positioning members; and controlling means including reversing levers connected with the positioning members, lever tripping members on the sound arms, locking levers for the shifting lever actuated by the tripping members prior to actuation of reversing levers, and lever shifting disks on the 95 driving shaft to actuate the shifting lever.

18. The combination with a picture taking or reproducing machine, of a sound recording or reproducing machine comprising a plurality of simultaneously operative record carrying members, hollow shafts therefor, record carrying pintles on the shafts for holding the records in inoperative position, means for locking the records to the 110 pintles, means for holding the pintles in operative engagement with the simultaneously operative record carrying members; a plurality of sound arms, record shifting means including a driving shaft having 115 lever shifting disks, the shaft connecting the talking and picture machines, a record shifting lever having pintle supporting means and lever positioning means thereon including catches engaged by the lever shift- 120 125 130

- ing disks and springs for the catches; and controlling means including reversing levers, lever tripping members therefor and locking means for the shifting lever.
- 5 19. In a machine of the class described, the combination of a moving picture taking or reproducing machine, a sound recording or reproducing mechanism comprising a plurality of simultaneously operable record-carrying members, means for effecting automatically the successive operation of the records carried by said members in repeated cycles, and synchronizing connections between said moving picture machine and said sound reproducing mechanism.
- 10 20. In a machine of the class described, the combination of a moving picture taking or reproducing machine, a sound recording or reproducing mechanism comprising a plurality of simultaneously operable record-carrying members, means for effecting automatically the successive operation of the records carried by said members in repeated cycles, and gear connection between said moving picture machine and said sound reproducing mechanism effecting synchronism thereof.
- 15 21. In a machine of the class described, the combination of a moving picture taking or reproducing machine, a sound recording or reproducing mechanism comprising a plurality of simultaneously operable record-carrying members, means for effecting automatically the successive operation of the records carried by said members in repeated cycles, and a common driving shaft geared to both said moving picture machine and said sound reproducing mechanism thereby producing synchronism thereof.
- 20 22. In a machine of the class described, the combination of a moving picture taking or reproducing machine, sound recording or reproducing mechanism comprising a plurality of record-carrying members, means for successively separating the operative connections between said members and the corresponding records, and for successively restoring said operative connections and synchronizing connections between said moving picture machine and said sound reproducing mechanism.
- 25 23. In a machine of the class described, the combination of a moving picture taking or reproducing machine, a sound recording or reproducing mechanism comprising a plurality of record carrying members, means for successively separating the operative connections between said members and the corresponding records, and for successively restoring said operative connection, means for effecting said separation and restoration in successive cycles, and synchronizing connections between said moving picture machine and said sound reproducing mechanism.
- 30 24. In a machine of the class described,
- the combination of a moving picture taking or reproducing machine, a sound recording or reproducing mechanism comprising a plurality of record-carrying members, means for successively lifting the records from the carrying members, means for successively depressing records into operative relation to said members, means for effecting said lifting and depressing in successive cycles, and synchronizing connections between said moving picture machine and said sound reproducing mechanism.
- 35 25. The combination with a picture taking or reproducing machine, of a sound recording or reproducing machine comprising simultaneously moving record carrying members, balanced successively operating record carrying members operated thereby, means for automatically locking the latter members alternately to the former members, laterally movable sound arms, upwardly moving record shifting mechanism operated thereby to raise the successively operable carrying members from the simultaneously movable members including a shifting lever, positioning members thereon, a shaft having catch carrying disks thereon, to engage said positioning members and controlling means including reversing levers operated by the sound arms to control the action of the disks upon the catches, said shaft having a synchronizing operative connection with said machines.
- 40 26. The combination of a moving picture taking or producing machine with a sound recording or reproducing machine having a plurality of record carrying members, means for holding a record in inoperative relation thereto, automatic means acting successively to effect operative relation between a record and a carrying member in repeated cycles, and a synchronizing operative connection between said machines.
- 45 27. The combination of a moving picture taking or producing machine with a sound recording or reproducing machine having a plurality of record carrying members, automatic means for successively throwing a record into operative relation thereto in repeated cycles, and a synchronized operative connection between said machines.
- 50 28. The combination with a motion picture taking or producing machine of a sound recording or reproducing machine comprising a plurality of record carrying members, means for inoperatively positioning a record relative thereto, automatic means for successively locking a record in operative relation to a carrying member in repeated cycles, and a synchronizing operative connection between said machines.
- 55 29. The combination with a motion picture taking or producing machine of a sound recording or reproducing machine comprising simultaneously operative carrying mem-

bers 15, shafts 9 therefor, record carrying pintles 17 therein for carrying the records in inoperative position, record locking members 18 on the pintles, members 20-21, 5 for holding the pintles in operative relation with the simultaneously operative carrying members, the sound arms 49, record shifting means including the driving shaft 11 connecting said machines and having the 10 disks 42 thereon, record shifting lever 24 with the pintles supports 22, lever positioning members 33-33^a, and catches 34 thereon adapted to be engaged by the lever shifting disks 42; and controlling means includ-

ing reversing lever 39, connected with the 15 positioning members 33-33^a, lever tripping members 30 on the sound arms, locking levers 29 for the shifting levers actuated by the tripping members prior to the actuation of the reversing levers. 20

In testimony whereof I have signed my name to this specification in the presence of two subscribing witnesses.

ALFONSO CORTELLA.
